UNITED STATES PATENT OFFICE.

WILLIAM P. COLLINS, OF SAN FRANCISCO, CALIFORNIA.

DESIGN FOR A DOOR HANDLE.

Application filed April 13, 1925. Serial No. 13,106. Term of patent 7 years.

To all whom it may concern:

Be it known that I, WILLIAM P. COLLINS, a citizen of the United States, residing at the city and county of San Francisco, State of California, have invented a new, original, and ornamental Design for a Door Handle, of which the following is a specification, reference being had to the accompanying drawings, forming part thereof.

Fig. 1 is a front elevation showing my design.

Fig. 2 is a side elevation of the same.

I claim:

The ornamental design for a door handle, substantially as shown.

WILLIAM P. COLLINS.
